RECORDING AND REPRODUCING
APPARATUS

Jan Jesayas Hardenberg, Eindhoven, Netherlands, assignor to N. V. Philips' Gloeilampenfabrieken, Eindhoven, Netherlands

Application January 12, 1937, Serial No. 120,317
In Germany January 15, 1936

1 Claim. (Cl. 242—55)

My invention relates to film recording and/or reproducing apparatus.

I shall describe my invention in connection with the recording and optical reproduction of sound-films, particularly narrow films driven by smooth-faced rollers, however, it is not limited thereto but is also applicable to the reproduction and recording of picture or sound-picture films.

In the present reproducing and recording apparatus a relatively long time is required to bring the film from rest up to its normal speed, i. e., the speed at which reproduction or recording can be effected without distortion. For example, in present apparatus for mechanical recording or 15 reproducing sound vibrations, the recording or reproducing needle can not be brought into its operative position on the film until after the film has attained its normal speed, as otherwise the variations in the starting speed of the film would cause distortions in the recording or reproduction. This results in a loss of film material and 20 also causes undesired delays in the recording or reproduction.

Such delays are particularly disadvantageous 25 when it is desired to reproduce only a selected portion of a sound film, as is frequently necessary in radio broadcasting studios. With present apparatus, due to the relatively long time required to bring the film up to its normal speed, 30 it is very difficult to reproduce a desired portion of a film without distortion, i. e., to start distortionless reproduction at exactly the beginning of the desired film portion.

Thus, in apparatus of the above type it is of 35 great importance that the film at the recording or reproducing point be brought from rest to its normal speed, or vice versa, as quickly as possible.

The object of my invention is to overcome the 40 above drawbacks, and to provide an apparatus in which distortionless recording or reproducing can be initiated or terminated simultaneously with the starting or stopping of the film at the recording or reproducing point.

In accordance with the invention, I drive the 45 film by friction from a driving mechanism, and provide braking or stopping means to immediately stop or release the film at the desired instance, whereas the driving mechanism continues to move at its normal speed. Thus upon release of 50 the braking means, the film is substantially instantaneously, i. e., within 0.2 sec. brought up to its normal speed by the driving mechanism which was already in motion.

In accordance with one embodiment of my invention, I provide a take-up film reel and a sup-

ply film reel which are driven or braked by friction, and drive the film by one or more constant-ly-rotating smooth-faced rollers disposed at points between these reels. In such an apparatus I so construct the film-driving mechanism 5 that the film slides over the surface of the smooth-faced rollers when the braking means stops the film.

If only a single smooth-faced driving roller is used between the take-up reel and the supply 10 reel, which latter reel is preferably braked by friction, I dispose the stopping means at a point behind this smooth roller. In referring to a point "behind" the roller is meant on the side of the 15 roller at which the film leaves. If a plurality of smooth-faced driving rollers are used, the stopping means should preferably be provided behind the roller nearest the take-up drum. Although such location of the stopping means is not absolutely necessary for carrying out my invention, it 20 has the advantage that it considerably reduces the friction between the film and the smooth-faced driving roller when the film is stationary.

As most apparatus of this type is provided with a thrust roller having a flexible surface pressing 25 the film against the smooth-faced driving roller, I prefer to disengage this thrust roller when the film is stopped by the braking means to thereby prevent the film being driven into a loop by the 30 combination of these rollers.

In order that my invention may be clearly understood and readily carried into effect I shall describe same in more detail with reference to the accompanying drawings in which:

Figure 1 is a plan view of a simple sound-film 35 reproducing apparatus embodying the invention.

Fig. 2 is a sectional view along line 2—2 of Figure 1.

Fig. 3 is a plan view of a sound-film reproducing apparatus according to another embodiment 40 of the invention.

Fig. 4 is a sectional view along line 4—4 of Fig. 3.

Fig. 5 is a view of a portion of Fig. 3 with an optical sound recording device applied thereto. 45

Fig. 6 is a view of a portion of Fig. 3 with a mechanical sound recording device applied thereto.

Fig. 7 is a view of a portion of Fig. 3.

The apparatus shown in Figs. 1 and 2 comprises a supply reel 2, a take-up reel 3, and a sound-reproducing arrangement comprising a film guide 6, a light source 9, and a photo-electric cell 10. A film 1 passes from reel 2 over a freely-rotatable guide roller 3, over the film guide 55

6 and a second freely-rotatable guide roller 7, and onto the take-up reel 8.

Disposed near reel 8 is a braking or stopping device comprising a lever 11 pivoted at 30 and carrying at one end a knob 12 of friction material, such as rubber. A tension spring 13 serves to press the knob 12 against the film with a pressure sufficient to immediately stop same.

Reel 8 is driven in the direction of the arrow 10 through a friction coupling. For this purpose, as shown in Fig. 2, reel 8 is carried by a shaft 19 provided on its lower end with a disc 23. Rotatably mounted on a fixed support 29 is a disc 17, provided with a coating 16 of friction material, for instance felt or fabric. Disc 17 is continuously rotated at a constant speed, as shown by a motor 30 through a friction wheel 31 engaging the periphery of disc 17.

Reel 8 is pressed against the coating 16 by means of a spring-biased lever 32 rotatable about a pivot 43 and acting upon the upper surface of disc 23. Thus, when lever 11 is placed in the position shown in Fig. 1, the film will be immediately stopped whereas the driving mechanism will 25 continue to rotate; reel 8 slipping upon the coating 16. Upon release of lever 11 the film almost instantaneously attains its normal speed and distortionless reproduction is obtained.

Reel 2 is mounted so as to be slightly braked. 30 For this purpose as shown in Fig. 2, reel 2 rotates upon a coating 34 of friction material such as felt, provided on support 29.

The apparatus shown in Figs. 3 and 4 is for the optical reproduction of sound which has been 35 mechanically or optically recorded on a film. One form of such an apparatus has been described in detail in my copending United States patent application Serial No. 103,460 filed September 30, 1936.

40 The apparatus shown in Figs. 3 and 4 is similar to that of Figs. 1 and 2 with the exception that the film passes around a thrust roller 4 and a smooth-faced driving roller 5 to keep the film at uniform speed before it reaches the film guide 6.

45 In this construction, smooth-faced roller 5 and reel 8 serve to drive film 1 at a uniform speed past the sound gate and for this purpose are driven by a motor (not shown). As such driving means are well known in the art further description or illustration of same is believed to be unnecessary. However it should be noted that roller 5 is directly and continuously driven whereas reel 8 is driven through a friction coupling in the manner described in connection with Figs.

50 1 and 2 or in a manner later to be described. Disposed near the sound gate is a braking device similar to that shown in Fig. 1.

As stated, roller 5 continues to rotate after film 1 is stopped, and thus might damage same if the 60 film were allowed to remain in contact with the surface thereof. However, as knob 12 is disposed so as to act upon the film at a point behind roller 5, i. e., at a point on the film leaving roller 5, film 1 becomes disengaged from roller 5, and 65 thereby will not be damaged.

To prevent film 1 from being continuously driven at the point of contact between roller 5 and thrust roller 4 and thereby forming an enlarged loop behind roller 4 and the point of contact of knob 12, I prefer to loosen the coupling between the rollers 4 and 5 when the braking device is closed. This may be effected in a simple manner by mounting roller 4 upon an extension 70 46 of a lever 45 whereby roller 4 will be moved 75 out of engagement with roller 5 when lever 45

is moved about the pivot 44 and the knob 12 will be placed in the position shown (see Fig. 7). However such construction is not essential to my invention, as in a simple apparatus such as shown in Figs. 1 and 2 the film is driven only by supply drum 8, and roller 5 and thrust roller 4 are eliminated. In such cases the knob 12 of the braking device may be disposed at any desired point, for example at the take-up drum 8 as shown in Fig. 1.

10 The apparatus shown in Fig. 3 may also be used for optically recording, for example by providing a suitable recording mechanism to produce the optical records on the film as it passes over the surface of roller 5. Such a recording mechanism is indicated by reference numeral 36 in Fig. 5.

The recording may also be effected mechanically at the point indicated by the arrow A in Fig. 3 by a suitable mechanical recording device.

20 For mechanical recording, a second thrust roller (not shown) is preferably provided at the point at which the film leaves roller 5. In this case, roller 4 acts only as a guide roller and may be removed from the periphery of roller 5, for instance may be rotatably mounted on a lever so as to guide the film.

25 Such a construction is illustrated in Fig. 6 in which reference numeral 37 indicates a mechanical recording device. In this case roller 4 serves only as a guide roller, and is rotatably mounted so as not to engage roller 5. A roller 38 rotatably mounted on a lever 40 pivoted at 41 and biased by a spring 42, presses roller 38 against roller 5 to thereby prevent slippage of film 1 upon the 35 surface of roller 5.

30 In such a construction in which the recording and reproducing are carried out on a single apparatus, the invention affords great advantages when the mechanical recording is effected in the manner described in the United States Patent No. 1,919,116 to James A. Miller. In such recording, a cutting tool having a V-shaped cutting edge with an apical angle of about 174° cuts an optically-reproducible vibration track in a carrier comprising a transparent film provided with 40 opaque covering layer. Such a vibration track, whose width variations are a proportional enlargement of its depth variations, can be electro-optically reproduced immediately after the recording, in the same apparatus and without additional means. This is of particular advantage for testing purposes, even during the recording.

45 By using an apparatus embodying the invention, one may immediately reproduce any selected portion which, in the operator's opinion, have been incorrectly recorded, and furthermore this may be effected in such a manner that the beginning of the portions in question can be previously adjusted exactly in front of the 55 scanning point. This advantage is brought out to a much higher degree when a selected portion of a film must be reproduced in a radio broadcasting station, as in such case it is absolutely necessary that the audience does not perceive 60 the starting of the film. However, with the apparatus according to the invention, this difficulty is practically eliminated in an extremely simple manner, as in such cases the required admissible starting time is about 0.1 second.

65 As in the apparatus shown in Fig. 3, film 1 is positively and immediately stopped by the braking device, reel 8 must also stop at the same time. For this purpose I drive reel 8 through a friction coupling in a manner indicated in Fig. 70 75

4. Referring to this figure, film 1 forms a roll upon reel 8, its end being clamped, for instance in a slit provided in a small disc 14 secured to reel 8. Reel 8 is fixedly mounted upon a shaft 18 carrying on its lower end a disc 23, whereas a thrust bearing comprising ball bearings 24 and a housing 25 having a cover 26, acts downwardly upon the upper surface of disc 23 with the aid of a tension spring 27.

10 Rotatably mounted upon a fixed bearing 18 is a hollow shaft 28 carrying a roller 21 and a disc 17 provided with a layer of friction material, such as felt or fabric engaging the lower surface of reel 8. Shaft 28 and disc 17 are driven at a substantially constant speed by means of a belt 22 driving roller 21. As suitable driving means for this purpose are well known in the art, further illustration or description of same is believed unnecessary.

20 Thus it will be seen that when film 1 is stopped by knob 12, rotation of drum 8 is also prevented, whereby the friction coupling formed by drum 8 and disc 17 and drum 8 slides over the layer 16. It will be noted that during the stationary periods of the film, disc 17 as well as various other members of the transmission system including roller 5 continue to rotate at their normal speed. Therefore upon releasing knob 12, film 1 will almost instantaneously acquire its normal speed, and the reproduction will not be affected by distortions.

Reel 8 may be driven or slightly braked through a weakly-driven friction coupling similar to that shown in Fig. 3. During the recording or reproducing process, reel 2 is preferably

rotated oppositely to the direction of this coupling whereby rotation of reel 2 is slightly braked. With such a device the film may be played back in a simple manner, the film in being returned to reel 2 being preferably led over a path different from its reproducing or recording path, for instance over a guide roller 28, as indicated in Fig. 3 by dotted lines. In this case, a device is usually provided by which the drive of the drum 8 is reduced and the drive of drum 2 is increased. 10 Such a device has been described in my above mentioned United States application Ser. No. 103,460.

While I have described my invention in connection with specific examples and applications 15 I do not wish to be limited thereto but desire the appended claim to be construed as broadly as permissible in view of the prior art.

What I claim is:

A film-driving apparatus comprising a supply 28 reel for the film, a take-up reel for the film, means for driving said take-up reel including a friction coupling, a roller for driving said film at a constant speed and having a smooth surface engaging the film, means to continuously 25 drive said roller, a thrust roller for pressing said film against said driving roller, means for stopping and releasing said film comprising a braking member adapted to engage the film at a point between said first roller and take-up reel, 30 and means connecting said member and thrust roller to disengage said thrust roller from said driving roller when said member engages the film.

JAN JESAYAS HARDENBERG. 35
